UNITED STATES PATENT OFFICE.

ALVIN HYDER, OF SAN PEDRO, CALIFORNIA.

OIL-ENGINE.

1,354,455.

Specification of Letters Patent. Patented Sept. 28, 1920.

Application filed February 10, 1919. Serial No. 275,976.

To all whom it may concern:

Be it known that I, ALVIN HYDER, a citizen of the United States, residing at San Pedro, in the county of Los Angeles and 5 State of California, have invented a new and useful Oil-Engine, of which the following is a specification.

This invention relates to internal combustion engines and more especially to the 10 ignition features thereof. The invention is not limited to the employment of oil in the operation of the engine and it is understood that the term oil signifies any fuel suitable for burning in an engine of the semi-Diesel 15 or analogous type of engine.

An important object of this invention is to make provision for the scavenging of burnt gases from the hot ball or vaporizer so that a comparatively small amount of 20 fuel injected into said hot ball will maintain the same at suitable temperature for ignition of the fuel.

Another object is to facilitate the operation 25 of the engine under idling conditions and changing from one condition to the other, especially from the idling to the load condition.

The type of engine shown in the drawings and embodying the invention is the, so 30 termed, semi-Diesel engine. This engine employs a hot ball or vaporizer and produces a comparatively high degree of compression of the charges previous to ignition thereof, the heat of combustion of the 35 charges of oil and air serving to maintain the vaporizers at the requisite temperature for ignition of the charges when said charges have been compressed by the engine.

In order to thoroughly understand some 40 of the advantages of this invention, it is noted that the ordinary semi-Diesel engine operates well under full load, that is to say, that when the engine is working under full load all of the cylinders fire substantially 45 regularly so that the power impulses are delivered to the shaft by the pistons working successively on their power strokes. When the load is removed, for instance when the clutch is thrown out to disengage 50 the driven shaft and its connected load from the engine shaft, quite often one or more of the engine cylinders cease to fire and the engine idles on the remaining cylinder or cylinders.

55 In the semi-Diesel type of engine a torch is employed to initially heat the hot ball

of each cylinder sufficiently to cause ignition of the charge supplied to the hot ball, and therefore it is readily understood that when it is desired to put a load on the engine operating at idling speed the hot balls of the inactive cylinders must be heated by their torches or any other suitable means before the cylinders will function.

As an example of one use of this type of 65 engine, when it is necessary to have the engine idle frequently and to have the engine pick up the load as quickly as possible, may be mentioned its use for propelling fishing boats. It is necessary in the operation of 70 fishing boats that their engines be idled frequently during the casting and hauling in of the fishing nets. Without this invention it is necessary to heat up the hot balls of the idle cylinders after each stopping of the 75 boat for the casting or hauling in of the nets so that said cylinders will again be put into operation.

In time the hot balls become filled with a carbonaceous mass which prevents proper 80 functioning of the engine. To remedy this objection in the operation of the engine, I have provided a third port in each of the hot balls so that the instroke of the piston will cause a certain degree of scavenging of 85 dead or burnt gases from the hot ball associated therewith. Not only is a scavenging effect produced, but the forcing of the hot gases through said third port, which is located in the outer end of the hot ball, 90 causes the outer portion of said hot ball to be maintained at a relatively high degree of temperature because the dead or exploded gases, ordinarily collecting in the outer portion of the hot ball, escape therefrom and 95 thus permit the hot gases from the cylinder to take the place of the dead gases and the hot gases thus have access to all portions of the walls of the hot ball. By thus maintaining the temperature of the outer 100 portion of the hot ball at a high degree, it is clear that the incoming oil charges are readily ignited and burned so that there will be no accumulation of unburned oil tending to cool the hot ball. This invention, in respect to the provision of the third port in the hot ball, is analogous to the hot ball construction in my copending application filed November 25, 1918, Serial No. 264,003. Whereas in said former invention the gases 110 were discharged from one hot ball to another to not only scavenge the dead gases

from that hot ball from which the gases are being discharged but to heat with burning gases the hot ball into which said gases are discharged, this invention provides in one 5 form for discharging the dead gases from the hot balls to the atmosphere, in another form provides for discharging the dead gases from the hot balls to the upper portion of the engine cylinders, and in still another 10 form provides for receiving the dead gases in a suitable chamber or tube so as to permit scavenging of the dead gases from all portions of the hot balls. Thus it is clear that in each form of this invention and in 15 said prior invention the hot ball is provided with a port through which the dead gases may be displaced from the hot ball by the hotter gases discharging into the hot ball from the cylinder on the scavenging stroke 20 of the piston. In all forms of this invention as well as in the prior invention the hot balls are maintained at temperatures sufficiently great to cause ignition of the fuel injected into them, even when the engine is idling.

Another object is to produce evenness of operation of the engine when idling and to avoid the production of excessive vibrations.

30 Other objects and advantages will appear in the subjoined detailed description.

The accompanying drawings illustrate the invention.

Figure 1 is a side elevation of an engine 35 embodying the invention, portions thereof being shown in vertical mid section and other portions broken away for clearness of illustration.

Fig. 2 is an enlarged plan view of the 40 engine cylinders and the ignition mechanism.

Fig. 3 is an enlarged sectional elevation on line indicated by x^3-x^3 , Fig. 2.

Fig. 4 is a plan section on line indicated 45 by x^4-x^4 , Fig. 3.

Fig. 5 is a sectional elevation on line indicated by x^5-x^5 , Fig. 2.

Fig. 6 is an elevation partly in section 50 on line indicated by x^6-x^6 , Fig. 2, the governor and air starting device also being shown in elevation.

Fig. 7 is a plan view of the cylinders of a modified form of the engine, showing the ignition mechanism in part.

55 Fig. 8 is a fragmental sectional elevation on line indicated by x^8-x^8 , Fig. 7.

Fig. 9 is a sectional elevation, analogous to Fig. 8 but on a smaller scale, of another modification of the invention.

60 The engine shown in Fig. 1 of the drawings, with the exception of the improvements hereinafter to be described, is a Fairbanks-Morse type "C-O" marine oil engine and is illustrated as being provided with three cylinders 1. It is understood that

the engine may have one, two or more cylinders. The engine governor is indicated at 2, the speed control lever at 3, the starting lever at 4, the pump at 5, the fuel pump lever at 6 and the clutch control lever at 70 7. Each of the cylinders 1 is provided with a piston 8, only one of which is shown in Fig. 1 of the drawings because of the nature of the view.

The upper end of that one of the cylinders 75 1 shown in section in Fig. 1 of the drawings is provided with or forms a hot ball or vaporizer 9 into which the charge is compressed on the upstroke of the piston, the vaporizer 9 having its open side communicating 80 through a port 10 with the piston chamber 11 of the cylinder. The vaporizer 9 is provided with suitable initial heating means for starting the engine into operation and such means in the instance shown in the drawings 85 comprises a starting tube 12 and a torch 13 adapted to play a flame upon the starting tube to heat the same. The vaporizer 9 is provided with a fuel intake port 14 connected by a fuel pipe 15 to a suitable source of 90 supply. The vaporizer 9 is provided with a port a connected by a tube 16 to a valve chamber 17 provided with a suitable valve 18 which, in the instance shown in the drawings, is in the form of a disk provided with a port 19 adapted when the disk is turned to port-opening position to register with an outlet port 20 in the valve chamber. The valve chamber and its valve may be of any other suitable construction than that shown 100 in the drawings though I have found that the ones described are very satisfactory in operation since the heat does not affect the valve's operation. The stem of the valve 18 is shown at 21 and said stem is turned by a 105 suitable arm 22, there being a spring 23 to hold the valve stem upward so as to hold the valve plate 18 tightly against the upper wall of the valve chamber in order to avoid leakage of gas past the disk valve. A stop 24 110 is provided in the valve chamber and said stop may be in the form of a screw projecting into the valve chamber and adapted to engage shoulders 25, 26 in the edge of the valve 18 to limit rotative movement of the 115 valve. But one port 19 is shown in the valve 18, but it is understood that if desirable a plurality of ports may be employed and if more than one is employed they will preferably be of different sizes. The parts 12 to 120 26 inclusive described above for the one cylinder are also employed for each of the other cylinders and those that are visible are designated on the drawings by the same reference characters.

125 Any suitable means are provided to simultaneously operate the arms 22 for opening and closing of the valves 18 and said means may be hand-operated if desired. I prefer that the valves 18 be opened and 130

closed automatically by operation of the governor 2 and for this reason the following described construction is provided. Pivot-
 ed at 28 to the arms 22 is a rod 29 which
 5 is screw-threaded at one end into a tubular
 slide 30 adapted to reciprocate in a sleeve 31
 supported by standards 32 fastened to any
 suitable support. In the instance shown in
 the drawings, see Fig. 6, the standards 32
 10 are fastened to the air starter body 33 of
 the engine. The sleeve 31 is provided dia-
 metrically thereof with a pin 34 passing
 through a slot 35 in the slide 30 and also
 through a slot 36 in a cam plate 37 which
 15 is fastened to one end of a rod 38 that is
 pivoted at its other end at 39 to the lever
 40 of the governor 2 so that operation of the
 governor will cause movement of the rod 38.
 The cam plate 37 is adapted to slide through
 20 longitudinal slots 41 in the sleeve 31 and
 through longitudinal slots 42 in the slide 30.
 The cam plate 37 is provided at its middle
 portion at opposite edges thereof with slant-
 ing faces 43, 44 respectively adapted to bear
 25 against the opposite ends of the slots 42, said
 slot ends thus forming abutments so that up
 and down movements of the cam plate 37
 will cause movements to the left and right
 respectively of the rod 29 in Figs. 1, 2 and 5
 30 of the drawings, movement to the left caus-
 ing the valve ports 19 to register with the
 ports 20 and movement to the right causing
 the valve ports 19 to be moved out of regis-
 tration with the ports 20. Speeding up of
 35 the governor 2 causes upward movement of
 the left end of the governor lever 40 in Fig.
 6 thus causing opening movement of the
 valves 18.

The governor lever 40 is connected to a
 40 rod 45 which forms a portion of the mecha-
 nism for controlling the length of a stroke
 of the pumps 5. This mechanism need not
 be described herein since it is of well known
 construction. In this particular engine up-
 45 ward movement of the rod 45 causes short-
 ening of the stroke of the pump plungers so
 as to cause the pumps to furnish less fuel to
 the engine cylinders when the speed of the
 engine increases.

50 From the foregoing it is seen that there
 is a direct relation between the fuel supply
 mechanism and the valve mechanism and
 that when the fuel decreases in volume the
 valves 18 open and when the fuel increases
 55 in volume the valves 18 close.

In the hereinbefore mentioned copending
 application the valve chambers 17 were con-
 nected to one another by tubing, but in this
 present invention other provisions are made
 60 for discharging the burnt gases from the
 valve chambers and the construction for
 effecting this is of various forms and will
 now be described. First referring to the
 form of the invention shown in Figs. 1 to 6
 65 inclusive, the ports 20 of the valve chambers

17 are connected by tubing 46 to ports 47
 in the walls of the respective cylinders 1,
 said ports being close to that end of the
 cylinders having the hot balls. Thus it is
 clear that, when the valves 18 are open, 70
 burnt gases discharging from the valve
 chambers 17 will, in reality, be caused to
 circulate through the upper portion of the
 cylinder and through the hot balls 9.

Now referring more particularly to the 75
 form of the invention shown in Figs. 7 and 8,
 the ports 20 of the valve chambers are con-
 nected by tubing 48 to the exhaust manifold
 49 of the engine. In the instance shown the
 tubing 48 connects with a single port 50 in 80
 the manifold, though it is understood that
 the tubing 48 from each of the valves may
 be separately connected to the manifold, if
 desired. In this form of the invention, when
 the valves 18 are open, the burnt gases are 85
 exhausted to the atmosphere by way of the
 manifold 49. This connection with the
 manifold is only for convenience and it is
 understood that the gases may be exhausted
 90 directly into the atmosphere, if desired, in-
 stead of by way of the manifold 49.

Now referring more particularly to the
 form of the invention shown in Fig. 9, the
 ports 20 of the valve chambers 17 communi-
 cate with gas receiving chambers 51 which 95
 in this instance are in the form of tubes
 closed at their outer ends by caps 52. By
 this construction the burnt gases, when the
 valves 18 are open, are displaced from the
 hot balls 9 into the valve chambers and 100
 thence into the chambers 51 on the up stroke
 of the pistons, and when the pistons return
 on their subsequent sucking stroke the
 burnt gases to some extent will flow out of
 the tubes 51. Thus with this form of the 105
 invention, though there is not actual circula-
 tion of the gases through the hot balls, there
 is a scavenging action since the gases are
 forced out through the ports a so that the
 110 hot gases from the engine cylinders will
 have access to the entire area of the walls
 of the hot balls and thus maintain them at
 the proper temperature for ignition of the
 fuel.

The operation of the invention is as fol-
 115 lows: Assuming that the engine is station-
 ary and that it is desired to start the same
 into operation and to operate it at idling
 speed, the torches 13 will be lighted to heat
 the vaporizers 9 in a manner well under-
 120 stood in the art pertaining to the semi-Diesel
 type of engine. When said vaporizers 9
 have been heated to the degree of tempera-
 ture sufficient for igniting the fuel, the
 starting lever 4 will be operated to admit 125
 compressed air to the cylinders, as is also
 well understood in this art, thus starting the
 pistons into operation.

130 Ignition of the charge compressed in the
 torch-heated vaporizers 9 will thereupon oc-

cur, thus starting the engine into self-operation, the speed of the governor being such as to raise the rod 38 and thus open the valves 18. The valves 18 being open, some 5 of the burning gases will discharge from the vaporizers 9 through the ports *a* into the tubes 16, thence into the valve chambers 17 and from the valve chambers through the ports 20. In the form of the invention 10 shown in Figs. 1 to 6 the gases discharging through the ports 20 will pass through the tubing 46 to the upper portion of the associated engine cylinders 1, thus making a circulation of the gases through the vaporizers. 15 In the form of the invention shown in Figs. 7 and 8 the burnt gases discharge from the hot ball through the tube 16 into the valve chamber, from the valve chamber through the tubing 48 and thence to the atmosphere 20 by way of the exhaust manifold 49. This allows fresh burning gases from the cylinder to reach all portions of the walls of the vaporizers 9 so as to maintain the same at the proper degree of heat for ignition of 25 the fuel. In the form of the invention shown in Fig. 9 the burnt gases are forced from the vaporizer 9 on the upstroke of the piston and said upstroke at the same time charges the vaporizer with burning gases so 30 as to maintain the vaporizer at the fuel-igniting temperature. The burnt or dead gases discharge from the vaporizer through the tube 16 into the valve chamber and from the valve chamber into the chamber 51. As 35 the piston moves down and up on succeeding strokes the gases first flow from the chamber 51 and then back into said chamber. Thus the chamber 51 serves as an enlargement of the valve chamber 17 so as to increase the capacity thereof. 40

When it is desired to connect the engine with the load, the lever 7 will be operated in the appropriate direction in a manner well understood in connection with this type 45 of oil engine, whereupon the governor owing to the slowing effect of the load on the engine, will decrease in speed, thus causing an increased amount of fuel to be supplied to the cylinders and at the same time effecting 50 closing of the valves 18. The increased amount of fuel maintains all of the vaporizers 9 at the requisite degree of temperature for igniting the compressed charges of fuel and air.

55 If the ports 19 in the valves be made of appropriate size, it is not necessary to close the valves when connecting up to the load, but it is preferable to do so to insure against overheating of the valve chamber 17 when 60 running under load. Now if it be desired to take the load off of the engine, the lever 7 will be moved in the appropriate direction to disconnect the engine shaft from the driven shaft, whereupon the governor 2 will speed up, thus causing a diminished supply 65

of fuel to be furnished to the engine cylinders and effecting opening of the valves 18 so as to allow scavenging of the dead gases from all portions of the vaporizers.

From the foregoing it is clear that with 70 this improved semi-Diesel engine all of the cylinders are in action when the engine is idling as well as when it is under full load and thus with the use of my invention the operation of the engine is even and less 75 vibratory than is the operation of former engines of this type, exclusive of that shown in the hereinbefore mentioned copending application.

It is understood that the invention is not 80 limited in its broader aspects to the details of construction shown in the drawings and described above, but that the invention includes such changes and modifications as can be construed as being within the spirit 85 and scope of the appended claims.

I claim:

1. In an oil engine, the combination with one of the cylinders and the governor thereof, of a piston for the cylinder, a vaporizer 90 for the cylinder communicating therewith, means to inject fuel into said vaporizer, a tube connected with the vaporizer, a valve chamber connected with said tube and provided with a port, a valve in the valve chamber to control the port, and means operatively connecting the valve with the governor.

2. In an oil engine, the combination with one of the cylinders and the governor thereof, of a piston for the cylinder, a vaporizer communicating with said cylinder, and means controlled by the governor for discharging some of the burnt gases from the vaporizer at higher speeds only of the governor. 100

3. In an oil engine, the combination with one of the cylinders and the governor thereof, of a piston for the cylinder, a vaporizer communicating with said cylinder, and means controlled by the governor for scavenging burnt gases from the vaporizer at 110 certain speeds only of the governor.

4. In an oil engine, the combination with one of the cylinders thereof, of a piston for the cylinder, a vaporizer communicating with said cylinder, and means for scavenging burnt gases from the vaporizer. 115

5. In an oil engine, the combination with the governor and one of the cylinders thereof, of a piston for the cylinder, a vaporizer communicating with said cylinder, means to inject fuel into said vaporizer, a tube connected with the vaporizer, a valve chamber connected with said tube and provided with 120 a port, a valve in the valve chamber to control the port, and means operative by increasing speed of the governor to open the valve and operative by decreasing the speed of the governor to close said valve. 125

6. In an oil engine, a cylinder, a piston for the cylinder, a vaporizer for the cylinder communicating therewith and provided with a port, means to inject fuel into the vaporizer, a tube leading from the port, a valve chamber connected with the tube and having a port, a valve to control the last named port, a tube connecting the last named port with the exhaust manifold, and means operatively connecting the governor with the valve. 40

5. In an oil engine, a cylinder, a piston for the cylinder, a vaporizer for the cylinder communicating therewith and provided with a port, means to inject fuel into the vaporizer, a tube leading from the port, a valve chamber connected with the tube and having a port, a valve to control the last named port, a chamber in communication with the last named port, and means operatively connecting the governor with the valve. 45

15. In an oil engine, a cylinder, a piston for the cylinder, a vaporizer for the cylinder communicating therewith and provided with a port, means to inject fuel into the vaporizer, a tube leading from the port, a valve chamber connected with the tube and having a port, a valve to control the last named port, a chamber in communication with the last named port, and means operatively connecting the governor with the valve. 50

20. In an oil engine, a cylinder, an exhaust manifold connected with the cylinder, a piston for the cylinder, a vaporizer for the cylinder communicating therewith and provided with a port, means to inject fuel into the vaporizer, a tube leading from the port, a valve chamber connected with the tube and having a port, a valve to control the last named port, means to operate the valve, and a tube connecting the last named port with the exhaust manifold. 55

25. In an oil engine, a cylinder, an exhaust manifold connected with the cylinder, a piston for the cylinder, a vaporizer for the cylinder communicating therewith and provided with a port, means to inject fuel into the vaporizer, a tube leading from the port, a valve chamber connected with the tube and having a port, a valve to control the last named port, means to operate the valve, and a tube connecting the last named port with the cylinder. 60

30. In an oil engine, a cylinder, an exhaust manifold connected with the cylinder, a piston for the cylinder, a vaporizer for the cylinder communicating therewith and provided with a port, means to inject fuel into the vaporizer, a tube leading from the port, a valve chamber connected with the tube and having a port, a valve to control the last named port, means to operate the valve, and a tube connecting the last named port with the cylinder. 65

35. In an oil engine, a cylinder, an exhaust manifold connected with the cylinder, a piston for the cylinder, a vaporizer for the cylinder communicating therewith and provided with a port, means to inject fuel into the vaporizer, a tube leading from the port, a valve chamber connected with the tube and having a port, a valve to control the last named port, means to operate the valve, and a tube connecting the last named port with the cylinder.

Signed at Los Angeles, California, this 3d day of February, 1919.

ALVIN HYDER.
